WELDER

Edward A. Hobart, Troy, Ohio, assignor to The Hobart Bros. Company, Troy, Ohio, a corporation of Ohio

Original application November 17, 1936, Serial No. 111,285. Divided and this application March 24, 1937, Serial No. 132,799

10 Claims. (Cl. 171—123)

This invention relates to welding apparatus, and in particular, to welders having a plurality of circuit arrangements for adapting the welder to differing load requirements.

5 One object of this invention is to provide an arc welder having a plurality of arrangements for the driving motor circuit, these arrangements being controlled by a switch which is actuated automatically in response to the variation in 10 load requirement of the welder.

Another object is to provide an arc welder having a driving motor in circuit with a star-delta switch which is automatically shifted in response to the attainment of a predetermined 15 load from star connection to delta connection, this shifting being accomplished, in one embodiment of the invention, by an electro-magnetic shifting arrangement arranged to give a time delay between the starting of the motor and the 20 shifting from the star to the delta connecting arrangement.

Another object is to provide an arc welder with the star-delta motor connection arrangement described immediately above, wherein the 25 star-delta switch-operating magnet is controlled by a relay, the coil of which is in series with the excitation circuit of the generator in such a manner that the relay is actuated to energize the star-delta shifting coil so as to shift the switch 30 from star to delta connections when the current in the excitation circuit reaches a predetermined value.

Another object is to provide an arc welder having a driving motor with a star-delta controlling switch operated automatically by electrical means, this electrical means being arranged to be energized in response to the attainment of a predetermined current in the generator excitation circuit, thereby providing a time 35 lag between the instant of starting the motor and the instant at which the star-delta switch is shifted to alter the connections of the motor from star to delta connections.

Another object is to provide an arc welder 40 of the type described in the preceding paragraph, wherein the star-delta switch-operating means is controlled by a switch arranged to be shifted when the output range switch of the welder is moved beyond a setting for a predetermined output.

Another object is to provide an arc welder according to the two preceding paragraphs, wherein a relay is provided for controlling the energization of the operating coils for shifting 45 the star-delta switch, the operating coil of this

relay being in series with the switch which is operated by the output range switch, the relay coil being arranged to be energized a predetermined period of time after the starting of the motor.

Another object is to provide an arc welder of the type described in the paragraph immediately above, wherein the operating coil of the relay is placed in the generator exciter circuit and energized when the excitation current reaches a predetermined value, thereby providing a time lag between the starting time of the motor and the shifting time thereof from star to delta connections.

This is a division of my application Serial No. 15 111,285, filed November 17, 1936, patented September 20, 1938, No. 2,130,584.

In the drawings:

Figure 1 is a wiring diagram for an arc welder embodying the control arrangement of this invention with the star-delta switch connecting the motor stator windings in star connection.

Figure 2 is a wiring diagram, similar to Figure 1, but with the star-delta switch shifted to connect the motor windings in delta connection.

Figure 3 is a side elevation of a portable arc welding outfit embodying the features of the present invention.

Figure 4 is a graphical illustration of the behavior of the arc welder of this invention in its 30 star and delta connections.

Figure 5 is a view of an oscillograph record showing the current draw for a given period of time after starting the motor, using the ordinary across-the-line starting arrangement.

Figure 6 is a view similar to Figure 5, but showing the oscillograph record of the current draw when the motor windings are shifted from star to delta connections, according to the present invention.

GENERAL ARRANGEMENT

In general, the arc welding system of this invention consists of a motor-driven arc welder having the motor windings brought out to the 45 terminals of a star-delta switch, means being provided to shift this switch from star to delta connections when the current draw in the output circuit exceeds a predetermined maximum. In the particular embodiment shown herein the energization of the star-delta switch-operating coils is controlled selectively by a relay switch, the operating coil of which is arranged to be energized a predetermined time after the starting 50 of the motor. The particular arrangement 55

shows the relay coil placed in series with the generator exciter output circuit so that the relay is operated to actuate its switch lever and shift the star-delta switch from the star to the delta position when the exciter has operated a sufficient period of time to produce sufficient current to energize and operate the relay.

Another switch is placed in series with the relay coil and positioned to be operated by the 10 output range switch which controls the output of the generator in such a manner that the series switch is normally open to prevent the energization of the relay, and hence, to disable the star-delta switch from being shifted from its star to its delta position when the current in the 15 excitation circuit exceeds a predetermined maximum. As the output range switch is shifted by the operator to set the generator for a higher output, this series switch is operated by the setting 20 operation when the range switch setting exceeds a predetermined value, thereby closing the disabling or series switch and enabling the relay coil to be energized when the current in the excitation circuit exceeds the amount necessary 25 for causing the relay coil to shift the relay switch.

Hitherto, workers in the welding art have sought to provide an arc welder having a driving motor which is adaptable to wide variations in 30 load requirements so that it may be called upon to pull a 50 per cent to 100 per cent overload, and yet be capable of running idle for considerable periods. It has been recognized that the ideal driving motor for such conditions must be 35 capable of carrying these overloads, yet must have good starting characteristics, a low power factor and low current consumption under a light load or no load at all. In many manufacturing plants, where there are many welders connected to the power line, several of the welders 40 may be running idle due to the workmen changing electrodes or setting up their work. At the same time, however, a heavy drain of current is withdrawn from the power lines and these 45 become overloaded because of this idle operating condition. If the motor is made adaptable to handle the heavy load of maximum requirements, it is found to draw an excessive amount of current when it is being started by an across- 50 the-line arrangement.

The present inventor, however, has found that by arranging the motor connections in a star-delta arrangement controlled by a star-delta switch which is operated automatically in response to the attainment of a predetermined current output, he is able to provide a motor which has a low current demand together with a high efficiency and a satisfactory power factor under idling or low-demand conditions, as when 55 a light welding operation is being performed where the full capacity of the machine is not being utilized. The present inventor has also found that a time lag is preferably provided to 60 allow the machine to build up its speed in star connection before the shift from star to delta connection is made, and brings this about by controlling the shifting or "throw-over" by a throw-over relay having its operating coil in 65 the generator excitation circuit. A disabling switch is inserted in series with this relay coil to disable the relay from energizing the star-delta switch shifting coils to shift the switch from star to delta positions when the output 70 range switch of the welding outfit is set for an 75

output below a predetermined value, such as for example, two-thirds of the maximum output attainable with the outfit. In this manner the setting of the welder for an output exceeding the critical output for the disabling switch enables the motor 8 to start in star connection and to be shifted to delta connection at a period of three or four seconds afterward, namely, when the excitation current increases to a predetermined amount. If, however, the output range switch is turned to 10 a reduced setting below the critical amount, the disabling switch is automatically opened, thereby preventing the relay from being energized to cause the star-delta switch to be shifted from its star to its delta arrangement. The machine, 15 under these conditions, starts at a low power consumption and is automatically shifted to the delta connection arrangement when the load demand requires a higher power current consumption. 20

Arc welder system

Referring to the drawings in detail, Figures 1, 2 and 3 show a typical arc welding system 25 arranged according to the present invention, Figure 3 showing a portable outfit. In Figure 3 there is shown an arc welder having a housing 10 supporting a rear axle 11 having rear wheels 12 thereon and secured thereto, as at 13. The 30 housing 10 is also provided with a yoke member 14 pivotally secured thereto, as at 15, and carrying an axle 16 having a single wheel 17 secured thereto, as at 18. A handle 19 is pivotally secured, as at 20, to the yoke member 14 and serves 35 the purpose of enabling the operator to pull the outfit from one position to another. The housing 10 at one end is provided with a motor sub-housing 21 and at the other end with a generator sub-housing 22. The housing 10 also 40 carries a superstructure 23 having a range switch, generally designated 24, attached thereto. Terminals 25 and 26 are provided for the attachment, respectively, of the welding electrode and ground connections of the generator. 45

Also mounted upon the superstructure 23 is a disabling switch 27 arranged to control the energization of a throw-over control relay, generally designated 28, which in turn, controls the shifting of a star-delta switch, generally designated 29. The sub-housing 21 contains a motor, generally designated 30, whereas the sub-housing 22 contains a generator generally designated 31, both of these being indicated diagrammatically in Figures 1 and 2. Coupled with the motor 30 55 so as to be driven thereby is an exciter 32 for producing the current required for the excitation of the generator field windings 33, connection being made therebetween through the field rheostat reversing switch 34 and the field rheostat 35 (Figures 1 and 2). Also included in the exciter output circuit is the winding 36, the operating coil 37 of the relay 28 and the disabling switch 27 operated by the output range switch 24. 60

The generator output circuit includes the winding 38, the tapped series winding 39, the electrode 40 and the ground or work-piece 41. The electrode 40 is connected to the tapped series windings 39 by the line 42, whereas the ground 41 is connected to the generator by the ground line 43, these connections being made, as previously stated, to the terminals 25 and 26 shown in Figure 3. The series windings 39 are tapped at the points 44, the leads 45 therefrom being brought out to the range switch contact points 70 75

48. The range switch 24 is provided with a switch arm 47 connected by the line 48 to the switch point 49 and line 50, leading to one end of the series windings 39. The range switch arm 47 is mounted upon a shaft 51 having a cam 52 arranged to shift the lever 53 of the disabling switch 27 at a predetermined point on the cam 52, this point corresponding to a predetermined setting of the switch arm 47. From the terminals of the disabling switch 27 the lines 54 and 55 run, respectively, to the exciter output line 56 and to the operating coil 37 of the relay 28, continuing on the opposite side thereof through the line 57 to the exciter output line 58. 10 The latter continues to a connection with one movable switch blade terminal of the field rheostat reversing switch 34, the other terminal being connected to the line 59 forming a continuation of the line 56 beyond the field rheostat 35. The field rheostat reversing switch 34 is provided with a resistance 60, shunted across two of its fixed terminals, the generator field windings 33 being shunted across the other fixed terminals. 15

20 The motor is provided with a shaft, indicated diagrammatically at 61, for operating the generator 31 and exciter 32. The motor 30 is of the three-phase type and is provided with stator windings 62, 63 and 64, with the opposite ends brought out to the terminals 65, 66, 67, 68, 69 and 70. 25 These terminals 65 to 70, inclusive, form one set of terminals of the star-delta switch 29, the opposite terminals 71, 72 and 73 being connected to the power current lines 74, 75 and 76. The star-delta switch 29 is provided with an operating shaft, diagrammatically illustrated at 77 and having mounted thereon the switch blades 78 to 83, inclusive. The switch blades 79, 81 and 83 are interconnected by the conductor 84, whereas the switch blades 78, 80 and 82 are of L-shaped form, 30 insulated from one another. The operating shaft 77 of the star-delta switch 29 is connected to means indicated by the numeral 85, responsive to the energization of the star magnet 86 or the delta magnet 87 to shift the shaft 77 and its switch blades 78 to 83, inclusive, from the star position, 35 shown in Figure 1, to the delta position shown in Figure 2, and vice versa.

40 Running from one of the power lines, such as the line 75, is a line 88 leading to the relay switch blade 89, the fixed terminals 90 and 91 of which are connected to the operating coils of the star and delta magnets 86 and 87, respectively, the opposite terminals thereof being interconnected by the line 92. A line 93 runs from the power 45 line 74 to the starting switch 94, thence through the stop switch 95 and auxiliary switch 96 to the coils of the star and delta magnets 86 and 87, completing the energization circuit thereof by way of the line 88 and relay switch blade 89.

50 In the arrangement shown in Figure 3 the disabling switch 27 is shown as operated by engagement with a pointer 97 mounted upon the movable dial 98 of the range switch, as distinguished from the cam 52 shown in Figures 1 and 2 for operating 55 the disabling switch 27. In Figure 3 the star-delta switch and the relay 28 are shown in diagrammatic form for clearness of disclosure. In practice, of course, they would be mounted on the superstructure 23 with the parts of the relay 60 28 concealed by a suitable cover.

Performance characteristics

Figure 4 shows graphically the performance of 75 a typical welding system constructed and ar-

ranged as shown in Figures 1 and 2. The horizontal values (abscissa) represent generator output in amperes at 40 volts, whereas the vertical values (ordinate) represent, according to the particular sets of curves, the motor ampere draw, the percentage efficiency, or the percentage power factor. From this graph it will be seen that the motor in star connection has a very low current draw in the lower ampere outputs, as compared with the delta connection, whereas in the higher 10 ampere range the delta connection has the lower current draw. The present invention takes advantage of both of these factors by employing the star connection for the lower current outputs with a low motor current draw, and the delta connection for the higher ampere outputs. These two 15 curves are designated "Star amps" and "Delta amps", respectively, in Figure 4.

The middle set of curves, designated "Delta eff" 20 and "Star eff", represent the comparative efficiencies of the two systems of connection with various ampere outputs. The vertical figures in this case indicate percentages of efficiency.

The highest pair of curves in Figure 4 is marked 25 "Delta power factor" and "Star power factor". They indicate the comparative performance of the driving motor as regards its star and delta connections, with particular reference to its power factor under varying ampere outputs of the generator at 40 volts. It will be seen from these curves 30 that the delta connection has a much lower power factor than the star connection at low ampere outputs, the star connection giving a much higher power factor in this neighborhood. In the higher 35 generator outputs, however, the delta connection gives a higher power factor than the star connection. The present invention also takes advantage of these circumstances to provide the most efficient arc welding system at both low and high 40 ampere outputs.

Figure 5 shows the oscillograph record produced by the oscillations of the oscillograph during the starting and subsequent period of operation for the ordinary across-the-line arrangement. This record shows that the motor initially 45 draws 176 amperes for a period of 1.62 seconds before this large current draw tapers off to the 16-ampere draw subsequently obtained. This record was produced by an oscillograph employed 50 with a 200-ampere arc welder with an across-the-line type of starter.

Figure 6, in contrast, shows the same arc welder 55 employed in connection with the star-delta arrangement of the present invention. The record of Figure 6 shows the starting current when the machine is started and before subsequent behavior, in a manner similar to Figure 5. In Figure 6, however, the motor is initially connected in the star arrangement and its current draw for the 60 initial period of 5.1 seconds is merely 58 amperes, in contrast with the 176-ampere current draw in Figure 5. As this current draw tapers off the throw-over devices operate to throw the system 65 into a delta connection, whereupon the current draw becomes 16 amperes, as shown in the middle section of Figure 5. In this manner the automatic throw-over from star to delta connection, and vice versa, reduces the load and consequent strains upon the power lines, and improves the 70 efficiency. It will be seen also that when the welding job is a light one, the welder is operated exclusively in a star connection so that it consumes but 58 per cent. of the current which would be 75 consumed in a delta connection.

Operation

The operation of the arc welder of this invention is largely apparent from the foregoing description. In operation the motor 30 is started with the circuit in the star arrangement, as shown in Figure 1, it being assumed that a light welding job is to be done. Under these conditions the range switch 24 is set with its switch arm 47 at a point below the point where the disabling switch 27 becomes closed so that the circuit through the operating coil 37 of the throw-over control relay 28 is open. As the generator 31 and exciter 32 come up to speed and produce current the throw-over control relay 28 is inoperative to effect the energization of the delta magnet 37, hence, the star magnet 86 remains energized and the delta magnet 87 deenergized. The switch blades of the star-delta switch 29 then remain closed, in the star position shown in Figure 1, and the subsequent operation occurs with the star connection of the motor stator windings. With the star arrangement, therefore, as shown in Figure 1, the motor 30 will consume a much lower amount of current than would be the case in the delta connection because the welding load being carried is a relatively small proportion of the rated capacity load of the welding outfit.

In Figure 2, however, the arm 47 of the range switch 24 is set for a high output, and the cam 52 automatically permits the disabling switch-operating arm 38 to shift and close the disabling switch 27. When this occurs the operating coil 37 of the throwover control relay 28 passes into closed circuit with the exciter 32, ready to be energized by the proper amount of current. The motor 30 is started as before, but during the initial period of its operation the relay 28 remains deenergized in the position shown in Figure 1. As the motor, the generator and the exciter come up to speed, however, after a period of three or four seconds, the exciter produces enough current to energize the relay coil 37 and cause the relay switch blade 88 to be shifted from the terminal 90 to the terminal 91. This action deenergizes the star magnet 86 and energizes the delta magnet 87. As a result of this the motor stator windings are disconnected from their star arrangement, as shown in Figure 1, and reconnected in their delta arrangement, as shown in Figure 2. This action occurs automatically without the requirement of any attention on the part of the operator other than to set the range switch 24 at the desired output.

It will be understood that I desire to comprehend within my invention such modifications as come within the scope of the claims and the invention.

Having thus fully described my invention, what I claim as new and desire to secure by Letters Patent, is:

1. In combination, a driving motor, a generator driven thereby, means for connecting the motor windings selectively in star and delta arrangements, and means responsive to the attainment of a predetermined generator current output for shifting said connecting means from star arrangement to delta arrangement.

2. In combination, a driving motor, a generator driven thereby, means for connecting the motor windings selectively in star and delta arrangements, and means connected to the generator output circuit and responsive to the expiration of a predetermined period of time after the starting of the motor in one arrangement for shift-

ing said connecting means to the other arrangement.

3. In combination, a driving motor, a generator driven thereby, said motor having a stator with a plurality of windings, means for connecting said windings selectively in star and in delta arrangements, and electrically-operated means responsive to the attainment of a predetermined generator output for shifting said connecting means from one arrangement to the other arrangement. 10

4. In combination, a driving motor, a generator driven thereby, said motor having a stator with a plurality of windings, switch means including an electromagnetic switch operator for connecting said windings selectively in star and 15 in delta arrangements, and means responsive to the attainment of a predetermined generator current output to selectively energize said operator for shifting said connecting means from one arrangement to the other arrangement. 20

5. In combination, a driving motor, a generator driven thereby, said motor having a stator with a plurality of windings, switch means including an electromagnetic switch operator for connecting said windings selectively in star and 25 in delta arrangements, and relay means normally operative to connect said windings in star arrangement and responsive to the attainment of a predetermined generator output after the starting of the motor in star arrangement to selectively 30 energize said operator for shifting said connecting means to delta arrangement.

6. In combination, a driving motor, a generator driven thereby, the windings of said motor being adapted to be changed from a starting arrangement in which a reduced voltage per turn is applied to a running arrangement in which normal voltage per turn is applied, means responsive to the attainment of a predetermined generator current output for initiating a change from one 40 arrangement of the windings to the other arrangement, a switching mechanism for completing said change, said mechanism comprising two sets of rotating contact members, the contact members of one set being connected together and the contact members of the other set being insulated from one another, and magnetic means responsive to said initiating means for rotating said members from a position in which the motor windings are connected in a star arrangement to 50 a position in which the windings are connected in a delta arrangement, whereby the voltage impressed across each turn of the motor windings is changed from a reduced value to the normal value after a starting period dependent upon the 55 attainment of a predetermined generator output.

7. In combination, a power generator, an exciting generator for energizing the field of the power generator, a motor for driving said generators, said motor having windings adapted to be 60 selectively connected such that a reduced voltage per turn is applied during the starting period of the motor and a normal voltage per turn after the starting period, and means responsive to the voltage developed by the exciting generator for 65 changing the motor winding connections from the reduced voltage per turn condition to the normal voltage per turn condition.

8. In combination, a power generator, an exciting generator for energizing the field of the 70 power generator, a motor for driving said generators, means for connecting the motor windings respectively in star and delta arrangement, and means responsive to the output current of said exciting generator for shifting said 75

- connecting means from the star arrangement to the delta arrangement.
9. In combination, a power generator, an exciting generator for energizing the field of the power generator, a motor for driving said generators, means for connecting the motor windings selectively in star and delta arrangement, and means connected to the armature circuit of the exciting generator for shifting said connecting means from star arrangement to the delta arrangement.
10. In combination, a power generator, an exciting generator for energizing the field of the power generator, a motor for driving said generators, means for connecting the motor windings selectively in star and delta arrangement, and means connected to the armature circuit of the exciting generator for shifting said connecting means from star arrangement to the delta arrangement.

10. In combination, a power generator, an exciting generator for energizing the field of the power generator, a motor for driving said generators, means for connecting the motor windings selectively in star and delta arrangement, and means including a relay connected in the field circuit of the power generator and in the armature circuit of the exciting generator for shifting said connecting means from the star arrangement to the delta arrangement.

EDWARD A. HOBART.
